DESIGN FOR A TEXTILE FABRIC

August Von Eisenbath, New York, N. Y., assignor to Ameritex-Sudanette, Div. of Cohn-Hall-Marx Company, New York, N. Y., a corporation of New York

Application July 27, 1933. Serial No. 48,842

Term of patent 3½ years

To all whom it may concern:

Be it known that I, AUGUST VON EISENBARTH, a citizen of the United States, residing at the city of New York, in the county of New York and State of New York, have invented a new, original, and ornamental Design for a Textile Fabric, of which the following is a specification, reference being had to the accompanying drawing, forming part thereof.

The figure is a plan view of a textile fabric, showing my new design. A single unit of my design is substantially shown on the drawing. The design as shown is one including a selvage. This selvage is shown at the bottom of the drawing.

I claim:

The ornamental design for a textile fabric, substantially as shown and described.
